UNITED STATES PATENT OFFICE.

GEORGE W. STEWART, OF CHICAGO, ILLINOIS.

DESIGN FOR A SIGNAL LANTERN.

Application filed March 29, 1922. Serial No. 1,442. Term of patent 14 years.

To all whom it may concern:

Be it known that I, GEORGE W. STEWART, a citizen of the United States, residing at Chicago, in the county of Cook and State of Illinois, have invented a new, original, and ornamental Design for Signal Lantern, of which the following is a specification, reference being had to the accompanying drawing, forming part thereof.

The figure is a view in elevation of a signal lantern, showing my new design.

I claim:

The ornamental design for a signal lantern, as shown.

GEORGE W. STEWART.
